CIRCUIT BREAKER OPERATING
MECHANISM

Benjamin P. Baker, Turtle Creek, Pa., assignor to
Westinghouse Electric Corporation, East Pitts-
burgh, Pa., a corporation of Pennsylvania

Application July 31, 1947, Serial No. 765,008

10 Claims. (Cl. 200—82)

1

This invention relates to circuit breakers and more particularly, to operating mechanism therefor.

One object of the present invention is to provide a circuit breaker embodying an improved operating mechanism of the fluid pressure operated type that is simple and rugged in construction and capable of efficient and reliable operation.

Another object of the invention is to provide a circuit breaker embodying an improved operating mechanism of the fluid pressure operated type wherein a single acting shock absorber is connected to the operating mechanism in a manner to retard the final movement of the mechanism in both opening and closing directions.

Another object of the invention is to provide a circuit breaker embodying a single acting shock absorber which is related to the breaker mechanism to retard movement of the breaker in both opening and closing directions.

The novel features that are considered characteristic of the invention are set forth in particular in the appended claims. The invention itself, however, both as to structure and operation, together with additional objects and advantages thereof, will be best understood from the following detailed description thereof when read in conjunction with the accompanying drawings.

In said drawings:

Figure 1 is a side elevational view, partly in section embodying the principles of the invention.

Fig. 2 is a front elevational view, partly in section of the operation mechanism.

Fig. 3 is an enlarged detail view showing the shock absorber and its connection to the breaker operating mechanism.

Fig. 4 is an elevational view, partly in section showing the shock absorber.

Fig. 5 is an enlarged sectional view showing the dashpot piston and valve.

Referring to Figs. 1 and 2 of the drawings, a storage tank 11 mounted within a metal frame 13 is provided for storing gas under pressure. Extending from the top of the tank 11 are three flanged conduits 15 which, in turn, carry metallic valve casings 17. A tubular insulator column 19 having a gas passage therethrough is mounted on the upper end of each of the valve casings 17 and an arc chute support 21 (only one being shown) also of insulating material is secured to the upper end of the tubular insulator 19. The support 21 has mounted thereon a stationary contact 23 (Fig. 1) provided with an external terminal connector 25. An arc chute 27 is also secured to the support 21 and the forward side of the arc chute is provided with a suitable opening (not shown) through which a movable contact blade 29 is operated into and out of engagement with the stationary contact 23. The lower

2

portion of the movable contact blade is bifurcated and the two legs thereof are pivoted at 31 to a conducting bracket 33 securely clamped about the tubular insulator 19. A terminal connector 35 extends from the right-hand side (Fig. 1) of the bracket 33, and serves, together with the terminal connector 25, to connect the interrupter in an electrical circuit.

The operating mechanism, indicated generally at 37, which is of the compressed gas operated type, is mounted within the frame 13 and includes an operating cylinder 39 (Figs. 1 and 2), an operating piston 41 reciprocably movable therein and a connecting rod 43. The connecting rod 43 is pivotally connected at its upper end by means of a coupling 45 to a pair of spaced arms 47 secured to an operating shaft 49 journalled in brackets 51 secured to the storage tank 11.

Arms 53 (Figs. 1 and 2), secured at spaced intervals to the shaft 49, are connected by means of insulating operating rods 55 to the movable contact arms 29 for the three poles of the breaker. The lower end of the connecting rod 43 is pivotally connected to a coupling member 57 which is secured to the piston 41 by means of a nut 59. A cylindrical guide member 61 threadedly engages an enlarged portion of the coupling 57 and extends upwardly through an opening in the upper end of the cylinder 39 forming an air-tight closure for the cylinder.

Each of the arms 53 is provided with a cam surface 63 which cooperates with a roller 65 carried by one arm of a bell crank 67. The bell crank 67 is pivoted at 69 on a suitable support and the other arm thereof can be brought into engagement with the stem 71 of a blast valve (not shown), suitably mounted in the housing 11. The blast valve normally closes an air blast passage in the insulator 19 and is opened by the cam 63 to admit a blast of compressed gas from the storage tank 11 through the insulator 19 to extinguish the arc drawn when the contacts separate.

45 The movable contact blade 29 is moved to the open position by the admission of compressed gas to the cylinder 39 above the piston 41 which moves the piston downwardly to the position in which it appears in Fig. 2. During the downward movement of the piston 41, the shaft 49 is rotated in counterclockwise direction by means of the connecting rod 43, and this movement of the shaft 49, acting through the operating rods 55, moves the contact blades 29 to the open position.

Upon admission of compressed gas to the cylinder 39 below the piston 41, the piston will be moved upwardly in the cylinder reversing the above-described operation and actuate the movable contact blade 29 to the closed position. In

the closed position, the arms 53 and the associated operating rods 55 form slightly overcenter toggles which maintain the contact blades 29 in the closed circuit position.

Compressed gas is admitted to the cylinder 39 to open and close the contacts by means of an opening inlet valve 73 (Fig. 2) and a closing inlet valve 75, both inlet valves being electromagnetically operated, and a control valve device indicated generally at 76. The valves 73 and 75 are connected to the storage tank 11 by means of pipes 77 and 79 (Fig. 1). The valve 73 communicates by means of a pipe 81 to a passage 83 in a housing 85 secured to an offset portion 87 of the cylinder 39. The passage 83 communicates with the upper end of a valve cylinder 89 and a passage 91 connects the cylinder 89 to the upper end of the operating cylinder 39. The upper end of the operating cylinder 39 also is provided with an exhaust port 93 which is normally closed by means of a cup-shaped piston type valve 95 forming a part of the control valve device 76.

The valve 75 is connected by means of a pipe 97 to a passage 99 in a housing 101 which is secured to an offset portion 103 of the main operating cylinder 39. The passage 99 communicates with the lower end of a valve cylinder 105 and this cylinder communicates with the lower end of the operating cylinder by means of a passage 107, communication between the passages 99 and 107 being normally closed by means of a cup-shaped piston type valve 109. The passage 107 also communicates with the atmosphere through an exhaust port 111. The piston valves 95 and 109 are mounted on opposite ends of a common valve rod 113 for simultaneous operation. The piston valves 95-109 are made hollow to limit their mass and provide for high-speed operation thereof.

Assuming the breaker to be in the open position as shown in Fig. 2, operation of the closing inlet valve 75 admits compressed gas from the storage tank 11 through pipes 77 and 79, valve 75 and pipe 97 to the passage 99 below the piston valve 109 moving the control valve device 76, to the uppermost position. The valve 95 in its upper position closes off the inlet passages 83-91 and opens the exhaust port 93. When the valve 109 moves to its upper position, it closes the exhaust port 111 and opens the communication between the passages 99-107 thereby admitting compressed gas to the operating cylinder 39 below the piston 41 to close the breaker. After the breaker is closed and the closing air below the piston 41 has bled to atmosphere, the control valve device 76 drops of its own weight to the lowermost position as shown in Fig. 2. In this position of the valves 95-109, the inlet passage 83-91 is open in readiness to admit a charge of opening gas upon opening of the inlet control valve 73.

The opening operation of the circuit breaker always takes precedence over a closing operation, that is, if the breaker closes in against a fault and the valve 73 is opened to admit a charge of opening gas to the cylinder 39 above the piston, the operation of the breaker will be quickly reversed and the breaker operated to the open position irrespective of the closing gas in the cylinder below the piston 41. This trip-free operation is accomplished by making the piston valve 95 of larger diameter than the piston valve 109. Consequently when, during a closing operation, the valve 73 is opened to admit compressed gas through the passage 81-83 to the top of the

piston valve 95. Due to the larger area of the valve 95, the compressed gas admitted above this valve overcomes the pressure below the smaller valve 109 and quickly forces the control valve device 76 downward to the lower positions. This quickly closes off the inlet passage 99-107, opens the exhaust port 111 to dump the closing charge of gas, closes the exhaust port 93 and opens the inlet passage 83-91 to admit compressed gas to the cylinder 39 above the piston 41, thus quickly reversing the direction of movement of the breaker mechanism and moving the breaker to the open position.

It will be observed that when compressed gas is admitted to the operating cylinder 39 on one side of the piston 41, the exhaust port 93 or 111 on the opposite side of the piston 41 is quickly opened by operation of the control valve device 76. This prevents trapping of gas on the non-working side of the piston which would slow down the operation of the breaker, thus providing for high-speed operation of the breaker to both open and closed positions.

In order to prevent slamming of the breaker parts, it is desirable to decelerate the movement of the breaker mechanism at the end of both opening and closing strokes. Dashpots and shock absorbers have been employed heretofore for decelerating the moving parts of the circuit breakers. However, in the past when deceleration was required at the end of both the opening and closing strokes, two dashpots were employed and these were suddenly engaged by the moving parts in a definite position in the stroke.

One of the features of the instant invention is the provision of a single shock absorber of the single-acting type connected to the operating mechanism of a circuit breaker in a manner to effectively decelerate the mechanism during the latter portion of both opening and closing strokes without sudden jerks or slamming of the parts. The single shock absorber, indicated generally at 115, is rigidly mounted on a channel member 117 forming a part of the metal frame 13. The shock absorber 115 is provided with an operating shaft 119 to which is rigidly secured an operating arm 121. The arm 121 is pivotally connected by means of a pair of links 123 to an arm 125 rigidly secured to the breaker operating shaft 49.

Referring to Fig. 4 of the drawing, a cam 127 disposed within the shock absorber housing is rigidly secured to the shaft 119 for movement therewith. The cam 127 is adapted to bear against a pad 147 mounted on a spider 149 formed integral with the end of a cup-shaped piston 129 disposed for movement in a cylinder 131 formed integral with the shock absorber housing. A compression spring 133 having one end bearing against the inside of the piston 129 and the other end seated against the bottom end of the cylinder 131 biases the end of the piston against the cam 127 and serves to return the piston following an action of the shock absorber. Disposed within the cup-shaped piston 129 is an intake valve 135 normally biased by means of a spring 137 to the closed position. The spring 137 is compressed between the valve 135 and a spring retainer 139. The end of the piston 129 is provided with a plurality of fluid passages, indicated at 141, which permit fluid to flow through an opening 151 in the upper end of the piston 129 into the cylinder 131 from a reservoir 142 during the return stroke of the piston.

A relief valve, indicated generally at 143, is

provided to control the flow of fluid out of the cylinder 131 during a compression stroke of the piston 129 to thereby control the retarding action of the shock absorber. The relief valve 143 is arranged to permit a small flow of fluid out of the cylinder during a relatively slow action of the shock absorber without opening the relief valve, but, upon the occurrence of a sudden heavy shock, the relief valve 143 opens, compressing a spring 145 which normally biases the valve closed, and permits a greater flow of fluid out of the cylinder 131 into the reservoir 142.

Referring to Fig. 3, the parts are shown in full lines in the closed circuit position of the breaker and are shown in dot and dash lines in the open circuit position of the circuit breaker. As viewed in Figs. 3 and 4, the shock absorber 115 is effective to decelerate the movement of the shaft 49 and the breaker mechanism only when the shaft 119 is rotating in clockwise direction, and is ineffective to restrain movement of the breaker mechanism when the shaft 119 and the cam 127 are rotated in a counterclockwise direction.

When the circuit breaker is operated to open position, the main shaft 49 together with the arm 125 (Fig. 3) rotates in a counterclockwise direction. During the first part of the opening movement, the arm 125, acting through the link 123, rotates the arm 121 and the shock absorber shaft 119 in a counterclockwise or non-restraining direction. When the toggle formed by the link 123 and the arm 125 crosses overcenter to the left of a line, indicated at A, drawn through the center of the shaft 49 and the pivoted connection of the link 123 to the arm 121, the direction of movement of the arm 121 is reversed and it starts slowly to move in the opposite or clockwise direction, hence the shock absorber offers little or no opposition to the opening movement of the circuit breaker until the accelerating period is over. The velocity of the arm 121 gradually increases, and the shock absorber becomes increasingly effective during the latter portion of the opening movement to decelerate the movement of the breaker mechanism, with maximum deceleration near full open position.

When the circuit breaker is operated to the closed circuit position, the arm 125 is moved in a clockwise direction from the position indicated by dot and dash lines at 125' (Fig. 3) to the full line position. During this movement, the arm 121 is rotated in a counterclockwise direction from the position indicated at 121'. In this direction of operation, the shock absorber 115 is ineffective to restrain the closing movement of the breaker mechanism. However, at about the time the contacts touch, the toggle 123-125 moves overcenter to the right of the line A, reversing the direction of movement of the arm 121 and the shock absorber is operated in the direction in which it is effective to retard the closing movement of the breaker mechanism.

The working pressure is maintained in the operating cylinder over the entire opening and closing strokes and also after the full open and closed positions have been reached. The purpose of maintaining full gas pressure after the contacts reach open position is to prevent rebound of the contacts toward closed position. During a closing operation, when the breaker is attempting to close in against heavy magnetic forces or stalling overloads, the full closing pressure is available. Maintaining the closing air pressure after the breaker is fully closed prevents rebound of the

toggle 53-55 from rebounding overcenter and thus holds the breaker closed. If, as previously described, the breaker closes in against a fault of sufficient magnitude, this breaker is immediately tripped open by operation of the control valve device 16 which dumps the closing air pressure and admits compressed gas above the piston to operate the breaker to the open position. After an opening or a closing operation is completed, the working pressure leaks out to the atmosphere.

It will be obvious that there is provided a single shock absorber of the single-acting type applied to a circuit breaker in a novel manner to decelerate movement of the breaker mechanism during the latter portions of both opening and closing strokes. The resistance of the shock absorber is applied gradually in both directions, consequently there is no sudden shock or jerk on the mechanism. Due to the toggle connection of the single-acting shock absorber to the breaker mechanism, the maximum decelerating force is applied near the full open and full closed positions which permits the full accelerating force to be maintained until the end of the stroke.

Having described the invention in accordance with the patent statutes, it is to be understood that various changes and modifications may be made in the structural details thereof without departing from some of the essential features of the invention.

I claim as my invention:

1. In a circuit breaker comprising a switch member movable to open and closed circuit positions, operating mechanism including a pivoted crank arm operable in opposite directions to effect opening and closing movements of said switch member, a dashpot operable in one direction to apply a retarding force and being ineffective to apply a retarding force when operated in another direction, an operating arm on said dashpot, connecting means connecting said operating arm and said crank arm having its line of action on said crank arm movable overcenter relative to the pivot of the crank arm so that movement of said crank arm in either direction first causes said operating arm to actuate said dashpot in ineffective direction and then in a direction to apply a retarding force to said crank arm.

2. In a circuit breaker comprising a switch member movable to open and closed circuit positions, operating mechanism including a crank arm movable in two directions to effect opening and closing movement of said switch member, a dashpot operable in one direction to apply a retarding force and being ineffective to apply a retarding force when operated in another direction, an operating arm on said dashpot, and a link connecting said crank arm to said operating arm, said link and said crank arm forming a toggle movable overcenter upon operation of said crank arm in either direction to first move said operating arm in ineffective direction and then to move said operating arm in a direction to apply a decelerating force to said operating mechanism.

3. In a circuit breaker comprising a switch member movable to an open and a closed circuit position, power operated operating mechanism including a crank arm operable in two directions to effect opening and closing movements of said switch member, a dashpot operable in one direction to apply a decelerating force to said operating mechanism, said dashpot being ineffective when operated in the other direction

to apply a decelerating force, an operating arm on said dashpot, and a link connecting said crank arm to said operating arm, said parts being constructed and arranged so that movement of said crank arm in either direction first moves said operating arm in ineffective direction and then moves said operating arm in a direction to cause said dashpot to apply a decelerating force to said operating mechanism.

4. In a circuit breaker, the combination of a switch member movable to an open position and to a closed position to open and close said circuit, power operated operating mechanism including a crank arm movable in two directions for moving said switch member to said open and closed positions, means comprising a single-acting dashpot for absorbing the kinetic energy of the moving parts of the circuit breaker, an operating arm on said dashpot and a link at all times connecting said crank arm to said operating arm, said parts being constructed and arranged to cause said dashpot to apply a decelerating force to said breaker mechanism near the end of an opening operation and also to apply a decelerating force to said operating mechanism at about the time the contacts touch during a closing operation.

5. In a circuit breaker, the combination of a switch member movable to open and closed positions to open and close the circuit, operating mechanism including a shaft operable in two directions to move said switch member to open and closed positions, power operated means for operating said shaft, a crank arm movable with said shaft, means comprising a single dashpot of the single-acting type for absorbing the kinetic energy of the moving parts of said circuit breaker, and a link operatively connecting said dashpot to said arm and movable overcenter to cause said dashpot to apply a decelerating force to said shaft during the latter part of the movement of said arm in either direction.

6. In a circuit breaker, the combination of switch means movable to open and closed positions, power operated operating mechanism including a crank arm movable in two directions for moving said switch means to open and to closed positions, a dashpot of the single-acting type for absorbing the kinetic energy of the moving parts of said circuit breaker, a rotatable operating arm on said dashpot, a linkage at all times operatively connecting said crank arm to said operating arm, said linkage being movable overcenter to cause said dashpot to apply a decelerating force to said operating mechanism when said operating mechanism moves in either direction, said linkage causing said operating arm to move first in reverse direction and to then apply the decelerating force near the end of each operating stroke.

7. In a circuit breaker, the combination of switch means movable to open and closed positions, power operated means including a crank arm movable in two directions for moving said switch means to open and to closed positions, a single dashpot of the single-acting type for absorbing the kinetic energy of the moving parts of the circuit breaker during both opening and closing operations, a rotatable operating arm on said dashpot, a link at all times connected to said operating arm and connected to said crank arm to form a toggle operable overcenter to first operate said crank arm idly in reverse direction

and then cause said dashpot to apply a decelerating force to said circuit breaker during movement of said operating mechanism in either direction.

8. In a circuit breaker, the combination of switch means movable to an open and to a closed position, operating mechanism comprising a cylinder and a piston operable therein, a crank arm operable in two directions by said operating mechanism for moving said switch means to both open and closed positions, inlet valve means for alternately admitting compressed gas to said cylinder on opposite sides of said piston to effect movement of said piston to open and closed positions, an inlet passage and an exhaust passage disposed adjacent each end of said cylinder, valve means operable by compressed gas admitted by said inlet valve means to open the inlet passage and close the exhaust passage on the working side of the piston and to simultaneously close the inlet passage and open the exhaust passage on the non-working side of the piston to effect high-speed operation of said circuit breaker, means comprising a dashpot of the single-acting type for absorbing the kinetic energy of the moving parts of the circuit breaker, and a link together connecting said dashpot to said operating mechanism and operable overcenter to cause said dashpot to apply a decelerating force to said operating mechanism during both opening and closing operations.

9. In a circuit breaker, the combination of relatively movable contacts operable to open and closed positions, power means comprising a fluid motor for operating said switch means, a crank arm operable in two directions by said motor to operate said contacts to both open and closed positions, a dashpot of the single-acting type for absorbing the kinetic energy of the moving parts of the circuit breaker and said fluid motor, valve means for energizing said fluid motor to effect operation of said switch member to open and closed positions, said valve means maintaining said fluid motor energized during the entire opening and closing operations, and a toggle connecting said single-acting dashpot and said crank arm and operable overcenter to cause said single-acting dashpot to apply a decelerating force to said circuit breaker during the latter part of an opening operation and also at about the time the contacts touch during closing operations.

10. In a circuit breaker, the combination of switch means operable to open and closed positions, power operating means comprising a fluid motor for operating said switch means, a crank arm operable in both directions by said motor to operate said switch means to both open and closed positions, valve means for energizing said fluid motor and for maintaining said motor energized during the entire opening and closing operations, decelerating means comprising a single-acting dashpot for absorbing the kinetic energy of the moving part of said circuit breaker, an operating arm on said dashpot, said link and said crank arm forming a toggle operable overcenter to cause said dashpot to decelerate the moving parts of the circuit breaker during the latter part of both opening and closing operations.

BENJAMIN P. BAKER.
